UNITED STATES PATENT OFFICE.

EDWARD WILLIAM ROBINSON AND CHARLES JEWELL ROBINSON, OF SAVANNAH,
GEORGIA.

SECURING HEADS IN WIRE-BOUND BARRELS.

1,320,924.

Specification of Letters Patent.

Patented Nov. 4, 1919.

Application filed November 24, 1917. Serial No. 203,716.

To all whom it may concern:

Be it known that we, EDWARD W. ROBINSON and CHARLES JEWELL ROBINSON, citizens of the United States, residing in Savannah, Georgia, have invented certain Improvements in Securing Heads in Wire-Bound Barrels, of which the following is a specification.

Our invention is an improvement upon 10 the method of securing heads in the ends of wire-bound barrels for which Letters Patent No. 1,197,153 were granted on the 5th day of September, 1916, the object of our present invention being to effect the secure retention of the barrel head without the use, 15 upon the latter, of the external batten which constitutes an element of the head shown in said patent.

This object we attain in the manner herein- 20 after set forth, reference being had to the accompanying drawings, in which—

Figure 1 is an end view of the barrel with the head in place therein but not secured thereto, and with a tightening band sur- 25 rounding the end portion of the barrel;

Fig. 2 is a similar view with the head secured in position in the barrel and with the tightening band removed;

Fig. 3 is an end view on a reduced scale 30 of the wire bound stave structure of the barrel, illustrating said stave structure as it appears when the parts are in the relation to each other shown in Fig. 1, and

Fig. 4 is an enlarged transverse section 35 on the line 4—4, Fig. 1.

In the drawings, the wire bound staves of the barrel are represented at 1, these staves, before the insertion and securing of the head in the barrel, being, at least so far as re- 40 gards their end portion, in the condition shown in Fig. 3, that is to say, being disposed in a segmental series with a gap α between the terminal staves of the series.

In order to close this gap a split hoop is 45 applied to the end of the series of staves, this hoop having a central channel member 2 for embracing the ends of the staves and being originally in the segmental form shown in Fig. 1, with a gap α' between its 50 ends. The outer flange of this channel hoop 2 bears against the outer faces of the staves and has a hollow bead 3 for embracing the external binding wire of the outermost pair, as shown in Fig. 4, and the inner flange of 55 the hoop bears against the inner faces of

the staves and has a radially projecting flange 5, as shown in Figs. 1 and 4.

The head of the barrel may consist of a single piece or it may be composed of any desired number of sections disposed side by side, as represented, for instance, at 6 in Fig. 1, the periphery of the head having formed therein, preferably midway between the top and bottom of the head, a kerf 7, whose depth may be equal to or slightly in 65 excess of the width of the flange 5, as shown in Fig. 4.

The first step in the operation of securing the head to the barrel is to engage the flange 5 of the end hoop with the kerf 7 when the 70 parts are in the position shown in Fig. 1, the extent of engagement of the flange with the kerf being, preferably, greatest at the point opposite to the gap α' in the hoop and gradually decreasing from that point to

ward the gap, at which latter point the flange may be entirely free from engagement with the kerf. A split clamping band 8 is now applied to the outside of the end hoop 2, and is gradually tightened by turn- 75

ing the screw stem 9 until the gap α between the terminal staves of the barrel and the gap α' between the ends of the hoop are closed, as shown in Fig. 2, the flange 5 of the 80 end hoop being now in full retaining en-

gagement with the kerf 7 throughout the entire periphery of the head. The hoop 2 can then be retained in its tightened position by means of any suitable fastening device, as for instance, by means of a staple 10 engag- 85

ing the meeting points of the hoop, as shown

in Fig. 2, the clamping band 8 having

formed therein, at a point opposite to the

tightening screw 9, a slot 11 for the introduc-

tion of said staple. 90

After the hoop has been thus secured in its tightened position, the clamping band 8 may be removed, as shown in Fig. 2, the engagement of the flange 5 of the hoop with the kerf in the periphery of the head serving 100 to effectually retain the latter against either inward or outward displacement, and also serving to prevent leakage around the head if there is a proper snug fit between the flange 5 and the kerf 7. 105

We claim:

The mode herein described of securing a head in the end of a wire bound barrel, said mode consisting in applying to the end of the wire bound set of staves, while the ter- 110

5 minal staves of the set are separated from one another, a split hoop having a flange projecting radially inward therefrom, said hoop likewise having separated ends, placing within said split hoop a complete head having a peripheral kerf therein, engaging with said kerf that portion of the flange of the hoop opposite the split ends thereof, surrounding the hoop by a split clamping ring
10 10 which contacts throughout its extent with the exterior of the hoop, then causing the ends of said split clamping ring to approach one another, thereby bringing to-

gether the terminal staves of the set and the ends of the split hoop and causing the 15 flange of the hoop to enter the peripheral kerf of the head throughout the circumference of said head, and then, while the hoop is still confined in the clamping ring, securing together the adjoining ends of the 20 contracted hoop.

In testimony whereof, we have signed our names to this specification.

EDWARD WILLIAM ROBINSON.
CHARLES JEWELL ROBINSON.
